UNITED STATES PATENT OFFICE.

OTTO BAYSDORFER AND GUSTAVE BAYSDORFER, OF OMAHA, NEBRASKA.

SPARK-PLUG.

1,188,529.

Specification of Letters Patent. Patented June 27, 1916.

Application filed August 4, 1915. Serial No. 43,597.

To all whom it may concern:

Be it known that we, OTTO BAYSDORFER and GUSTAVE BAYSDORFER, citizens of the United States, residing at Omaha, in the county of Douglas and State of Nebraska, have invented certain new and useful Improvements in Spark-Plugs, of which the following is a specification.

This invention relates to an improvement 10 in spark plugs for use in connection with internal combustion engines, and has for its principal object to provide a spark plug found to be particularly useful in instances where an alternating current is employed 15 for electrically igniting the compressed gas so that the ignition will not be intermittent. Another object is the production of a greater heat than ordinary for the electric spark, in the presence of compressed gas. 20 Other objects of the invention relate to such a construction that a comparatively less amount of electrical energy will be required for operation than usual, and that the injury to magnetos and coils occurring occasionally during their use, will be 25 avoided.

The invention broadly includes the combination of a pair of electrodes each having a comparatively extensive, smooth area and 30 a projection, the electrodes being so arranged that the smooth and extensive area of one electrode will be disposed adjacent to and near the projection of the other electrode, so that the electric current, while alternating, will readily and uniformly travel 35 from one electrode to the other.

In instances where magnetos and their connections or coils are employed for producing electrical energy for actuating the 40 sparking to cause ignition, irregular or intermittent action of the spark plugs tends to injure the magneto or coil so that frequent repairs are required. By use of the herein described spark plug, the delay and expense 45 thus caused, for the most part, may be avoided. Also in instances where electric batteries are employed, their connections and polarity are sometimes carelessly reversed by an operator, so that closures of 50 the electrical current are made with difficulty. It is considered that, by use of the spark plug described herein, no inconvenience or defect in operation whatever will arise by reason of any change in polarity of 55 the batteries.

It is understood that, in the construction

of spark plugs, two electrodes have heretofore been provided with spherical surfaces and disposed adjacent to each other to produce a shower of sparks; also that a plurality of projections have been provided for one electrode and disposed adjacent to a companion electrode having a smooth or plain surface so that the electric current could travel on the projection providing a 60 passageway of least resistance or greatest attraction; and for the same purpose a plurality of projections have been provided for both electrodes of a spark plug; and it is also understood that these constructions are 65 for use only in instances where there is to be uniformity in travel of the electric current, and if the electric polarity in those structures should be changed, their operation would be defective for the reason that 70 the electric circuit could not be completed 75 with equal facility in both directions.

By a recently conducted experiment, where two electrodes were mounted to extend within a glass receptacle so that sparking could be observed, said receptacle containing air under pressure and the electrodes being energized by a magneto, said electrodes being constructed substantially as shown in the present drawings, it was discovered that the electric sparking occurred 80 in alternation, or in other words it occurred between the projection of a first electrode and the smooth surface of a second electrode, and next between the projection of 85 the second electrode and the smooth surface of the first electrode.

The object of the invention therefore is to provide such a construction for a spark plug that the electric sparking will occur 90 between two electrodes regardless of the polarity of the electrical supply.

With the foregoing objects in view the invention consists of the novel construction, combination and arrangement of parts as 100 described herein and claimed, and as illustrated in the accompanying drawing, where-

in. Figure 1 is a view of a spark plug in longitudinal section, illustrating one embodiment of the invention. Fig. 2 is a broken away detail relating to Fig. 1, to show the surface of a ball provided for the insulated electrode. Fig. 3 is an enlarged, broken away detail, in section, to illustrate a modified form of the invention.

Referring now to the drawing, numerals

4 in the several views, indicate a part of a cylinder of an internal combustion engine in which is mounted a plug or cylindrical bushing 5 called, for convenience of description, the ground electrode, and providing an annular chamber in communication with the cylinder of the engine, a rod or electrode 6, suitably insulated by the block or envelop 7, being disposed centrally of the 10 annular wall 8 of the ground electrode and provided, as shown in Figs. 1 and 2, with a ball or member 9 having a smooth and preferably convexed surface, and also provided with a prong or projection 10 extending in a direction of the annular wall 8.

Numeral 11 indicates a projection with which the annular wall 8 is provided, and which extends in a direction of member 9.

It will be understood that if a magneto is 20 employed for providing electrical energy, the electrodes 5 and 6 will be charged with positive electricity in alternation. In operation, when the electrode 5 is charged with positive electricity, the spark will occur between the projection 11 and the convexed surface of member 9, and when the electrode 6 is charged with positive electricity, the spark will occur between the projection 10 and the adjacent smooth surface 8 of the electrode 5. On account of the construction thus provided, the sparking, regardless of the degree of compression of the gas, will be effected without intermitting and will be intensified, injury to the magneto or coil will 35 be prevented and a very limited voltage, only, will be required for operation.

Fig. 3 illustrates a modified form of the invention, wherein the electrode 6 is provided with a transverse arm 12, one end 40 thereof having a ball or convexed member 9' mounted thereon and disposed adjacent to the projection 11 of the annular wall 8, its opposite end being provided with a tapered part 10' adapted to be disposed adjacent to the smooth surface of wall 8, and by use of this construction it is obvious that operation would be substantially the same as already described.

While we have described construction in 50 detail, we do not wish to be understood as limiting ourselves in this respect, nor to size, form, proportion or material to be employed, since the scope of the invention is determined by the claims.

We claim,—

1. In a spark plug for engine cylinders, the combination of a first electrode having an annular chamber in communication with a cylinder and provided with an angular projection extending inwardly of said chamber, an insulated electrode having a convexed

part disposed centrally of the annular chamber of the first electrode adjacent to the angular projection of said first electrode, said convexed part of the insulated electrode 65 being provided with an angular projection extending outwardly of its surface to be disposed adjacent to the wall of the annular chamber of the first electrode.

2. A spark plug, including a pair of electrodes each having a smooth surface with an angularly projecting part, said electrodes being disposed adjacent to each other, the angularly projecting part of the smooth surface of each electrode extending toward 75 the smooth surface of the adjacent electrode.

3. In combination, a ground electrode having a concaved area with an angular projection, an insulated electrode having a convexed area with an angular projection, said electrodes being disposed adjacent to each other, the angular projection of the ground electrode extending toward the concaved area of the insulated electrode and the angular projection of the insulated electrode 85 extending toward the concaved area of the ground electrode.

4. In combination, a ground electrode, an insulated electrode, each having a smooth area with an angular projection, said electrodes being disposed adjacent to each other, the angular projection of the smooth area of each electrode extending toward the smooth area of the other electrode.

5. In a spark plug, the combination with 95 a ground electrode having a transversely curved wall formed rectilinear throughout its length and provided with an angular projection extending inwardly thereof, of an insulated electrode having a smooth part 100 disposed adjacent to the angular projection of the ground electrode and provided with an angular projection extending toward the transversely curved rectilinear wall of the ground electrode.

6. In a spark plug, the combination with a ground electrode having a transversely curved wall provided with an angular projection extending inwardly thereof, said wall having a uniform bore throughout its length, 110 of an insulated electrode having a smooth part disposed adjacent to the angular projection of the ground electrode and provided with an angular projection extending toward the wall of the ground electrode.

In testimony whereof, we have affixed our signatures in presence of two witnesses.

OTTO BAYSDORFER.
GUSTAVE BAYSDORFER.
